Primary Examiner — Bridget L Eland*Assistant Examiner* — Lauren McVey(74) *Attorney, Agent, or Firm* — Renner, Otto, Boisselle
& Sklar, LLP(57) **CLAIM**The ornamental design for a nasal dilator, as shown and
described.**DESCRIPTION**The sole FIGURE is a front view of a nasal dilator showing
our new design, a rear view thereof being a mirror image of
the front view, the nasal dilator being substantially flat so
that side and end views thereof are substantially a line.
The broken lines are for the purpose of illustrating portions
of the nasal dilator that form no part of the claimed design.**1 Claim, 1 Drawing Sheet**| (56)	References Cited
